HEADER FOR A MOTORCYCLE EXHAUST SYSTEM

George J. Kryssing, 254 Madison Ave.,
Brentwood, N.Y. 11717

Filed Mar. 20, 1972, Ser. No. 236,539

Term of patent 14 years

Int. Cl. D12—16

U.S. Cl. D14—6 D

FIG.1

FIG.4

FIG.2

FIG.5

FIG.3

FIG.6

FIG.7

FIG. 1 is a perspective view of the front and side of the header for a motorcycle exhaust system showing my new design;

FIG. 2 is a front view;

FIG. 3 is a rear view;

FIG. 4 is a top view;

FIG. 5 is a side view;

FIG. 6 is a bottom view; and

FIG. 7 is a side view opposite that of FIG. 5.
I claim:

The ornamental design for a header for a motorcycle exhaust system, as shown.
